US0D1041446S

(12) **United States Design Patent** (10) **Patent No.:** **US D1,041,446 S**
(45) **Date of Patent:** **** Sep. 10, 2024**

(54) **HEADPHONE**

(71) Applicant: **Shenzhen Shrythm Industry Co., Ltd.**, Shenzhen (CN)

(72) Inventor: **Jiao Peng**, Shenzhen (CN)

(**) Term: **15 Years**

(21) Appl. No.: **29/921,978**

(22) Filed: **Dec. 20, 2023**

(30) **Foreign Application Priority Data**

Oct. 24, 2023 (CN) 202330689053.9

(51) **LOC (14) Cl.** **14-01**

(52) **U.S. Cl.**

USPC **D14/205**

(58) **Field of Classification Search**

USPC D14/205, 188, 192; D29/112; 2/209;

(57) **CLAIM**

The ornamental design for a headphone, as shown and described.

DESCRIPTION

FIG. 1 is a perspective view of a headphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
